SYSTEM FOR PRODUCING AMPLITUDE-
MODULATED PULSESWilliam D. Houghton, Port Jefferson, N. Y., as-
signor to Radio Corporation of America, a cor-
poration of Delaware

Application May 9, 1947, Serial No. 747,105

21 Claims. (Cl. 332—14)

1

This invention relates to a method of and means for producing amplitude modulated pulses of relatively opposite polarities in a communication transmitter system.

More specifically, the invention enables the production of plus and minus amplitude modulated pulses. The pulses generated in the system of the invention may have a positive polarity, a negative polarity or be of zero amplitude, depending upon the amplitude and polarity of the modulating voltage. When the modulating voltage is zero, no pulses are generated. When the modulating voltage is maximum and negative, the amplitude of the generated pulse is a maximum in one direction, and when the modulating voltage is maximum and positive, the amplitude of the generated pulse is a maximum in an opposite direction. The variations in amplitude of the generated pulses are made to be linear with respect to the modulating voltage.

The invention is especially useful in multi-channel (multiplex) time division systems wherein in a common transmission line is sequentially assigned to different channels each of which has its own modulation applied thereto. The common transmission line may feed any suitable radio frequency generator or transmitter circuit for modulating the carrier wave, but it is preferred to utilize the amplitude modulated pulses to shift the frequency of a frequency modulation transmitter about its mid-carrier frequency; and since no pulses are produced in the absence of modulation, full advantage may be taken of the noise limiting qualities of a frequency modulation system.

A more detailed description of the invention follows in conjunction with a drawing, wherein:

Fig. 1 illustrates, diagrammatically, the transmitting end of a multi-channel pulse communication system in which the invention may be employed;

Fig. 2 illustrates the circuit details of a channel unit and the common output equipment embodying the principles of the invention;

Fig. 3 is a series of curves graphically illustrating voltage waveforms at different points of the circuits of Figs. 2, 4 and 5 given in explanation of the operation of the invention; and

Figs. 4 and 5 show other embodiments of the invention.

Referring to Fig. 1 in more detail, this figure shows transmitting apparatus for a plurality of channels each of which is supplied with its own signal modulation. A crystal oscillator A is employed to lock in a pulse oscillator B. The out-

2

put from pulse oscillator B is coupled through lead 111 to a step voltage wave generator G. The step voltage wave output from generator G is coupled through lead 112 to the inputs of a plurality of channels suitably labeled as channel units 1, 2, 3, etc. Each channel unit produces two simultaneously occurring pulses whose amplitudes are differentially modulated in accordance with the modulation applied to that channel. The two pulses from each channel unit are fed to a common channel combining unit 124 which converts the two pulses to a single pulse whose amplitude is modulated plus and minus about zero or ground potential. The variations in amplitude of this single pulse are made linear with respect to the modulating voltage. Channel units 1, 2 and 3 are shown diagrammatically connected to the channel combining equipment 124 over leads 118, 119 and 120, respectively. A synchronizing pulse generator D produces a synchronizing pulse of longer duration than the channel output pulses immediately after the discharge of the step wave generator G, and is controlled by the generator G over lead 113. The combined channel output pulses from combining equipment 124 plus the synchronizing pulse are fed to the common amplifier 125, which amplifies the pulse train in preparation for modulating a radio frequency transmitter T. The synchronizing pulse generator D is coupled to the amplifier 125 through lead 117, while the amplitude modulated channel pulses from the common channel combining unit are fed to this same amplifier over lead 130.

The crystal oscillator A produces a sine wave output whose positive or negative portion controls the production of a pulse from pulse oscillator B. The oscillator A may be any L. C. or R. C. type depending upon the stability requirements of the system. The pulse oscillator B may be a blocking type pulse oscillator which produces D.-C. pulses at the frequency of the crystal oscillator A. The time constants of the pulse oscillator B are so chosen that the natural frequency of operation of the pulse oscillator is slightly lower than the frequency of the crystal oscillator.

The step wave generator G produces a stair or step voltage wave having a plurality of risers of substantially the same amplitude range but of different voltage values relative to a base line. A condenser in the step wave generator stores or collects the incremental charges passed thereto by the pulse oscillator, until a predetermined peak or total voltage is reached after which it discharges. There are two outputs from the step wave generator, one of which is the stair or step

voltage wave available on lead 112 and the other of which is the discharge pulse available on lead 113.

For a more detailed description of suitable circuits which may be used for the crystal oscillator A, pulse oscillator B and step wave generator G, reference is made to my copending application Serial No. 608,957, filed August 4, 1945.

Fig. 2 illustrates the circuit details of a channel unit, it being understood that all channel units are identical except for the bias adjustment. This figure also illustrates the common channel combining equipment 124 which is fed by all channels.

Each channel unit includes a selector vacuum tube 6 which is biased to be normally non-conducting by an adjustable tap 50 on the cathode resistor 8. It will thus be seen that resistor 8 is variable. The step wave output from the step wave generator is fed to the grid of the tube 6 through a grid current limiting resistor 1. Resistor 1 limits the maximum grid-to-cathode potential. The tube 6 is biased so that it becomes conducting on a particular riser of the applied step voltage wave. When tube 6 becomes conducting, the current in this tube rises from zero to a maximum value and remains at this maximum value for the duration of the applied step wave. The condenser 7 in parallel to the cathode resistor 8 serves to bypass A.-C. components of cathode current to ground. The anode of tube 6 is connected through resistor 2 to the positive terminal B+ of a source of D.-C. potential.

It should be understood at this time that the inputs of all selector tubes in the different channels are fed in parallel by the applied step voltage wave, and that the selector tubes in the different channels are differently biased to become conducting on different risers of the applied step wave, as a result of which the pulses produced in the different channels occur sequentially at different time intervals.

The anode of selector tube 6 is also coupled to the grid of a normally conducting vacuum tube 9 through a condenser 5. The grid of tube 9 is also connected through a resistor 3 to the terminal B+. The combination of condenser 5 and resistor 3 forms a differentiator circuit. The anode of tube 9 is connected to the same B+ terminal through a resistor 4, while its cathode is connected to ground through a resistor 10.

A pair of triode vacuum tubes 11 and 12 of similar characteristics have their cathodes directly connected together and to the cathode of tube 9, as a result of which resistor 10 is a common cathode resistor for all three vacuum tubes 9, 11 and 12. The flow of current through normally conducting tube 9 produces a voltage drop across resistor 10 which is sufficient to bias tubes 11 and 12 below cut-off. The value of resistor 10 is so chosen that when tube 9 ceases conducting, the reduction of the bias voltage developed across this resistor enables tubes 11 and 12 to operate as class A amplifiers. For this reason, tube 9 can be considered as a "gate."

A source of audio modulation for the channel is supplied to the grids of tubes 11 and 12 in push-pull or out-of-phase relation through transformer 13. The anodes of tubes 11 and 12 are individually connected to the B+ terminal through equal value resistors 14 and 15, respectively, and are also coupled through condensers 16 and 17, respectively, to the grids of vacuum tubes 28 and 20.

Tube 20 acts as a class A amplifier and has its anode connected through a resistor 18 to the B+ terminal, and connected through a coupling

condenser 19 to the grid of a triode vacuum tube 21 also operating as a class A amplifier.

Tube 28 also operates as a class A amplifier and has its anode directly connected to the anode of amplifier tube 21. Both amplifiers 21 and 28 are identical. A common load resistor 29 connects the anodes of the two tubes 21 and 28 to the B+ terminal. The cathodes of tubes 21 and 28 are directly connected together, and to ground through a common cathode resistor 27.

The anodes of tubes 21 and 28 are coupled through a condenser 30 to the grid of a triode vacuum tube 33 operating as a class A amplifier. The anode of tube 33 is connected through a resistor 31 to the B+ terminal, and is also connected through a coupling condenser 32 to the output lead 130 extending to the common amplifier 125. Plus and minus (positive and negative) amplitude modulated pulses are derived from the common channel combining equipment 124 on lead 130. The manner in which this is accomplished will now be described more fully.

Tube 6 is biased to be normally non-conducting and is made to start conduction on any desired step riser by adjusting the value of the bias voltage developed across variable cathode resistor 8. When tube 6 becomes conducting its anode potential suddenly drops to a low value, causing normally conducting tube 9 to be cut-off. Tube 9 remains cut-off for a time determined by the time constants of the differentiating network 3 and 5. Vacuum tubes 11 and 12 are normally non-conducting due to bias developed across resistor 10 when tube 9 is conducting. The value of resistor 10 is so chosen that when tube 9 is cut-off, tubes 11 and 12 are biased as class A amplifiers. Hence, two negative going pulses (one across resistor 14 and one across resistor 15) are developed when tube 9 is cut-off. The duration of these negative pulses is equal to the cut-off time of tube 9, and is determined by the differentiating network 3 and 5. When no modulation is present on the channel, the two pulses are equal in amplitude. When modulation is present on transformer 13, the amplitude of the pulses vary linearly in a push-pull manner. That is, as the pulse across resistor 14 increases in amplitude, the pulse across resistor 15 decreases in amplitude by an equal amount.

The operation of the common circuit is as follows: The negative pulse across resistor 15 is coupled to class A amplifier 20. The amplification factor of 20 is made unity, hence a positive pulse equal in magnitude to the negative pulse across resistor 15 is developed across resistor 18. Tube 20 can thus be considered a phase inverter tube. The pulse developed across resistor 18 is coupled to the grid of class A amplifier 21, while the pulse developed across 14 is coupled to the grid of class A amplifier 28.

For the condition where the channel is unmodulated, the negative pulse across resistor 14 is equal in amplitude to the negative pulse across resistor 15. The positive pulse across resistor 18 is equal in magnitude but 180° out of phase with the pulse across resistor 14. Therefore, since the grid of tube 21 is driven positive by the same amount the grid of 28 is driven negative, there is no voltage change across resistor 29 and no pulse present to drive output tube 33. For the condition where modulation is present on transformer 13 and the grid of tube 12 is made more positive than the grid of tube 11, the negative pulse across resistor 15 is greater in amplitude than the negative pulse across resistor 14. Hence

the positive pulse on the grid of tube 21 is greater in amplitude than the negative pulse on the grid of tube 28 and a negative pulse is developed across resistor 29 which results in a negative pulse being applied to the grid of tube 23, and as a consequence a positive pulse being developed at the terminal 130. For the condition where modulation is present on transformer 13 and the grid of tube 11 is made more positive than the grid of tube 12, the negative pulse across resistor 14 10 is greater in amplitude than the negative pulse across resistor 15. This results in the grid of tube 28 being driven more negative than the grid of tube 21 is driven positive, and hence a positive pulse is developed across the grid of tube 23 resulting in a negative pulse being developed 15 at terminal 130. The amplitude of the pulses on lead 130 vary linearly with the modulating voltage.

Fig. 3, curve A shows the step voltage waveform as applied to the grid of selector tube 6. The lower dashed line labelled P indicates the potential above which tube 6 is biased to conduct, while the upper dashed line labelled X indicates the potential above which the grid to cathode potential of tube 6 reaches zero. Fig. 3, curve B shows the wave form developed between the anode of tube 6 and ground. When tube 6 becomes conducting its anode potential suddenly drops to a low value and remains at this value for the remainder of the applied step voltage wave cycle.

Fig. 3, curve C represents the waveform developed across cathode resistor 10 which is common to tubes 9, 11 and 12, the dash-dot line labelled Y indicates the potential below which tubes 11 and 12 become conducting. The length or duration of these pulses is determined by the R. C. constants of differentiating network 3 and 5 which differentiate the negative going edge of the anode voltage wave of tube 6, Fig. 3, curve B.

Fig. 3, curve D shows the waveform of the modulating voltage applied to the grid of tube 11, and Fig. 3, curve E the waveform of the modulating voltage applied to the grid of tube 12. The waveform of Fig. 3, curve E bears a 180° out-of-phase relationship with that of Fig. 3, curve D.

Fig. 3, curve F represents the negative going pulses on the anode of tube 12, and Fig. 3, curve G the negative going pulses on the anode of tube 11. It will be seen at time R, S, and T the negative pulses of Fig. 3, curve F and Fig. 3, curve G are equal in amplitude. This is due to the fact that at the time of conduction of tubes 11 and 12, the applied modulating signals are passing through zero.

Fig. 3, curve H shows the positive pulses at the grid of tube 21. These pulses are equal in amplitude but 180° out-of-phase with those appearing on the anode of tube 12 (Fig. 3, curve F).

Fig. 3, curve I shows the plus and minus pulses as they appear on lead 130 at the output terminal. It should be noted that there are no pulses appearing at times R, S, and T since at these points the two sine waves Fig. 3d and 3e are at zero amplitude and the positive pulses in Fig. 3h are equal and opposite to those in Fig. 3g; resulting in the increase in current in tube 21 being exactly balanced by the decrease in current in tube 28. This balance occurs when tubes 11 and 12 are made conducting at a time when the modulating waves applied to their grids have zero amplitude. At all other times, a pulse will appear and will

be either positive or negative depending upon which tube 11 or 12 carries the greater amount of current when it is made conducting.

In multiplex systems, the time interval between adjacent pulses, curves F, G and H of Fig. 3, contain all the other channel pulses. It will thus be seen that the final output pulses from each channel are either positive or negative in sign and are amplitude modulated. The final output pulses from the different channels occur at different time intervals. For each cycle of operations represented by a single complete step voltage wave, there will be a pulse from each channel unit in the presence of modulating voltage, and this pulse will be either positive or negative, and the pulses from the different channels occur sequentially. In the output of the common amplifier 128, each cycle of operations will also include a synchronizing pulse of longer duration than the channel pulses and which occurs at the end of the step voltage wave, or after all the channels have each produced one pulse. The synchronizing pulse may have an amplitude equal to or slightly greater than the maximum amplitude of any channel pulse under extremes of modulation. The synchronizing pulse may be smaller in amplitude if the receiving equipment is designed to accept it.

Figs. 4 and 5 show other embodiments of the invention which are not as desirable as Fig. 2 when using a large number of channel units, on account of the greater tendency for cross-talk in the systems of Figs. 4 and 5, but are desirable for smaller systems due to their simplicity. The same parts which appear in all three figures have been given the same reference characters.

Figs. 4 and 6 employ a transformer 60 in the channel unit for producing the desired plus and minus output pulses. The operation of Fig. 4 40 may be understood by reference to the curves A to I of Fig. 3. Fig. 3 curve A shows the step voltage wave applied to the grid of selector tube 6. Let it be assumed that the tube 6 of Fig. 4 is so biased as to become conductive on the second riser of the step wave of Fig. 3, curve A. The horizontal dash line p in Fig. 3, curve A indicates the point of conduction and the horizontal dash line x indicates the level at which the grid-to-cathode potential of tube 6 reaches zero. The anode potential of tube 6 is shown in Fig. 3, curve B for the condition assumed above. On the negative going edge of the voltage wave across resistor 2, the normally conducting gate tube 9 is cut-off for a time interval determined 50 by the time constants of differentiating network 5, 3. The negative pulses of the curve C of Fig. 3 indicate the intervals during which tube 9 is cut-off. When tube 9 is cut-off the potential across resistor 10 drops, as a result of which tubes 11 and 12 conduct and act as class A amplifiers during the cut-off time of tube 9.

Fig. 3 curves D and E indicate the audio modulation voltage applied to the grids of tubes 11 and 12 by transformer 13. These voltages are identical but 180° out-of-phase, that is, transformer 13 feeds the grids of 11 and 12 in a push-pull manner well known in the art. The waveform F of Fig. 3 represents the negative voltage pulses appearing on one-half of the primary winding of transformer 60 due to current in tube 12 while Fig. 3 curve G represents the negative voltage pulses appearing on the other half of the primary winding of 60 due to current in tube 11. Curve I of Fig. 3 represents the plus and minus pulses as they appear across the secondary winding of

transformer 60. It will be noted that there are no pulses appearing at times R, S, and T in Fig. 3, curve I since at these times the modulating voltage is passing through zero and the voltage on the grid of tube 11 is equal to the voltage on the grid of tube 12 and hence they carry equal currents when conducting and since transformer 60 is a push-pull type there is no change in voltage across the secondary winding. However, in the presence of an audio voltage on transformer 13, if the grid-to-cathode potential of tube 11 is made more positive than the grid-to-cathode potential of tube 12, a pulse is developed across the output winding of transformer 60 of a polarity depending upon the connections of the transformer. On the next half cycle of the audio voltage, tube 12 carries more current than tube 11 and hence a pulse of opposite polarity is developed across the output winding.

Fig. 5 shows a modification of the system of Fig. 4 in which push-pull transformer 13 of Fig. 4 is replaced by a phase inverter tube 49. The operation of this circuit follows:

A step voltage wave as shown in curve A of Fig. 3 is coupled to the grid of normally non-conducting tube 6. Tube 6 is biased to become conducting on a particular step riser as previously described. When tube 6 becomes conducting its anode potential suddenly drops to a low value (see curve B of Fig. 3) and remains at this low value for the remainder of the step wave cycle. The negative going or falling edge of the voltage wave on the anode of 6 is differentiated by the differentiating network consisting of 3 and 5. Thus a negative pulse is developed on the grid of normally conducting tube 9 sufficient to cause it to cease conducting. Tube 9 remains cut-off for a period of time determined by the values of 3 and 5.

When tube 9 is conducting it develops a voltage across resistor 10 sufficient to maintain tubes 11 and 12 cut-off. Hence when tube 9 cuts off tubes 11 and 12 become conducting. The value of 10 is so chosen that tubes 11 and 12 operate as class A amplifiers during the time they are conducting. The voltage developed across resistor 10 is as shown in curve C of Fig. 3.

Tube 49 is a conventional phase inverter tube which produces a voltage across its plate resistor which is equal to and 180° out-of-phase with the voltage developed across its cathode resistor. The voltage developed across the anode resistor 20 of tube 49 is coupled to the grid of tube 11 via coupling condenser 16 and the voltage developed across the cathode resistor 18 of tube 49 is coupled to tube 12 via coupling condenser 17. Elements 114 and 115 are the grid leak resistors for tubes 11 and 12 respectively. The modulating signal appearing across grid resistor 114 is shown in curve D of Fig. 3 and the signal appearing across resistor 115 is shown in curve E of Fig. 3.

The negative pulse voltage across one-half of the primary of 60 due to pulse currents in tube 12 is shown in curve F of Fig. 3, while the negative pulse voltage across the other half of the primary of 60 due to pulse currents in 11 is shown in curve G of Fig. 3. The resulting plus and minus amplitude modulated pulses are shown in curve I of Fig. 3.

It should again be noted that when the tubes 11 and 12 conduct when the modulating voltage is passing through zero no voltage is developed on the secondary of 60. This is due to tubes 11 and 12 carrying equal currents. When the voltage on the grid of one tube has a magnitude greater

than that on the other and when they become conducting (tubes 11 and 12) a pulse will appear on the output, the polarity being a function of the tube carrying the greater current and the amplitude being a function of the degree of unbalance in the grid voltages.

It will be understood that it is not necessary to employ individual tubes for the triode electrode structures, since if desired, a dual or twin triode tube can be used which contains two electrode structures within a single evacuated envelope.

What is claimed is:

1. In a pulse generating system, the method which includes producing two simultaneously occurring pulses of the same relative polarity, differentially modulating said pulses in accordance with a signal, and converting said two pulses to a single pulse whose amplitude is modulated plus or minus relative to a reference value.

2. In a pulse generating system, the method which includes producing a pair of simultaneously occurring pulses of the same relative polarity, equalizing the amplitudes of said pulses in the absence of modulation, varying the amplitudes of said pulses differentially and linearly in accordance with a modulating signal, and converting said pair of differentially modulated pulses to a single pulse which has one polarity when one pulse of said pair has a larger amplitude than the other, and which has an opposite polarity when said one pulse has a smaller amplitude than the other.

3. In a pulse generating system, the method which includes producing two simultaneously occurring pulses of equal amplitude and of the same relative polarity, modulating the relative amplitudes of said pulses in accordance with a modulating voltage, controlling the flow of space current in one path by one of said pulses, controlling the flow of space current in another path by the other of said pulses, balancing out the effects of the flow of current in said paths when the pulses are of equal amplitude, causing a greater flow of current in one path compared to the other path when said pulses are of different amplitudes, and utilizing said difference in current flow to produce a pulse in one direction or the other depending upon which path has the greatest current flow.

4. In a pulse generating system, the method which includes producing first and second simultaneously occurring pulses of negative polarity and of equal amplitudes, differentially modulating the amplitudes of said negative pulses in accordance with a modulating signal, obtaining a positive pulse from said first negative pulse and of the same relative amplitude, controlling the flow of space current in one path by said positive pulse,

5. In a pulse generating system, the method which includes producing first and second simultaneously occurring pulses of negative polarity and of equal amplitudes, differentially modulating the amplitudes of said negative pulses in accordance with a modulating signal, obtaining a positive pulse from said first negative pulse and of the same relative amplitude, controlling the flow of space current in one path by said positive pulse, controlling the flow of space current in another path by said second negative pulse, balancing out the controlling effects of said positive and said second negative pulses, only when said first and second negative pulses have equal amplitudes, and utilizing any difference in the controlling effects caused by said differential modulation to produce a pulse whose sense depends upon which path carries the greater flow of current and whose magnitude depends upon the extent of the difference in current flow in the two paths.

6. In a pulse generating system, the method which includes producing a pair of simultaneously occurring pulses of the same relative polarity, equalizing the amplitudes of said pulses in the absence of modulation, varying the relative amplitudes of said pulses linearly in accordance with

7. In a pulse generating system, the method which includes producing a pair of simultaneously occurring pulses of the same relative polarity, equalizing the amplitudes of said pulses in the absence of modulation, varying the relative amplitudes of said pulses linearly in accordance with

a modulating signal, and converting said pair of pulses to a single pulse whose amplitude is a linear function of the modulating voltage and which has one polarity when one pulse of said pair has a larger amplitude than the other, and which has an opposite polarity when said one pulse has a smaller amplitude than the other.

6. A pulse generating system comprising a first vacuum tube electrode structure biased to be normally non-conducting, a circuit for supplying a recurring waveform to said first structure of a polarity and magnitude to render it conducting at the frequency of said waveform, a second vacuum tube electrode structure biased to be normally conducting, a differentiator circuit coupled between the output of said first structure and the input of said second structure, to thereby cause said second structure to cease conducting in response to the conduction condition of said first structure, a pair of space current paths controlled by the condition of said second structure, said space paths being biased to be non-conducting in the normal conduction condition of said second structure and passing current during the non-conducting condition of said second structure, means for differentially controlling the flow of current in said space paths in accordance with a modulating voltage, and means for deriving from said space paths a pair of differentially modulated pulses having variations in amplitude which are linear with respect to the modulating voltage.

7. A pulse generating system comprising a pair of electrode structures each including an anode and a control element, cathode means for said structures, a bias element in circuit with said cathode means for normally biasing said electrode structures below cut-off, individual impedances in circuit with the anodes of said structures, a circuit for periodically overcoming the cut-off bias of said structures to thereby render them conducting, a modulating circuit coupled to said control elements in push-pull relation, and means coupled to said impedances for deriving differentially modulated pulses.

8. A pulse generating system comprising a pair of electrode structures each including a cathode, an anode and a grid, a common cathode resistor for said structures, individual resistors connected between said anodes and the positive terminal of a source of D.-C. potential, a circuit for causing current to flow periodically through said cathode resistor to thereby periodically cause said electrode structures to conduct, means coupled to said grids for supplying a modulating voltage to said grids in opposing phase relation, and leads coupled to said individual resistors for deriving therefrom a pair of simultaneously occurring pulses of the same relative polarity but whose amplitudes vary in dependence upon the modulating voltage.

9. A pulse generating system comprising a pair of electrode structures each including a cathode, an anode and a grid, a common cathode resistor for said structures, individual resistors connected between said anodes and the positive terminal of a source of D.-C. potential, a circuit for causing current to flow periodically through said cathode resistor to thereby periodically cause said electrode structures to conduct, means coupled to said grids for supplying a modulating voltage to said grids in opposing phase relation, leads coupled to said individual resistors for deriving therefrom a pair of simultaneously occurring pulses of the same relative polarity but whose amplitudes vary in dependence upon the modulating voltage, and electronic means for converting said pair of pulses

to a single pulse whose polarity depends upon which electrode structure of said pair passes the greater amount of current and whose magnitude depends upon the extent of difference in the amounts of current flow through both electrode structures.

10. A pulse generating system comprising a pair of vacuum tube electrode structures, each including a control electrode and an anode, a circuit for periodically causing said structures to become simultaneously conductive and then non-conductive, a circuit for supplying a modulating voltage to the control electrodes of said pair of structures in out-of-phase relation, and leads coupled to said anodes for deriving from said structures a pair of simultaneously occurring pulses of the same relative polarity when said structures simultaneously change from one current condition to the other.

11. A pulse generating system comprising a pair of vacuum tube electrode structures, each including a control electrode and anode, a circuit for periodically causing said structures to become simultaneously conductive and then non-conductive, a circuit for supplying a modulating voltage to the control electrodes of said pair of structures in out-of-phase relation, individual resistors connected between the respective anodes and the positive terminal of a source of D.-C. potential, and means connected to said anodes for deriving therefrom a pair of simultaneously occurring pulses of negative polarity when said structures change from the non-current passing condition to the current passing condition.

12. A pulse generating system comprising a pair of vacuum tube electrode structures, each including a control electrode and anode, a circuit for periodically causing said structures to become simultaneously conductive and then non-conductive, a circuit for supplying a modulating voltage to the control electrodes of said pair of structures in out-of-phase relation, individual resistors connected between the respective anodes and the positive terminal of a source of D.-C. potential, a phase inverter amplifier coupled to the anode of one of said structures, a second amplifier coupled to the anode of the other structure, a third amplifier coupled to the output of said phase inverter, a common load resistor for said second and third amplifiers, and means coupled to said common load resistor for deriving therefrom a pulse whose polarity may be either plus or minus depending upon which one of said electrode structures carries the greater current during the time both electrode structures are simultaneously conductive.

13. A pulse generating system including means for producing a pair of simultaneously occurring pulses of the same polarity whose relative amplitudes vary linearly in response to a modulating voltage, and means for converting said pair of pulses to a single pulse whose polarity depends upon which one of said pair of pulses has the greater amplitude and whose amplitude depends upon the extent of difference in amplitudes of said pair of pulses.

14. In a pulse generating system, the method which includes producing two simultaneously occurring pulses of equal amplitude and of the same relative polarity, differentially modulating the amplitudes of said pulses in accordance with a modulating voltage, controlling the flow of space current in one path by one of said pulses, controlling the flow of space current in another path by the other of said pulses, balancing out the effects of the flow of current in said paths when

the pulses are of equal amplitude, causing a greater flow of current in one path compared to the other path when said pulses are of different amplitudes, and utilizing said difference in current flow to produce a pulse in one direction or the other depending upon which path has the greatest current flow, said last means comprising a phase inverter amplifier fed by one of said pulses of said pair, a second amplifier coupled to the output of said phase inverter, and a third amplifier fed by the other pulse of said pair, there being a common load resistor for said last two amplifiers, and an output circuit coupled to said common load resistor.

15. A system for converting a pair of simultaneously occurring pulses of the same polarity and whose amplitudes vary differentially in accordance with a modulating voltage to a single pulse, including a phase inverter amplifier fed by one of said pulses of said pair, a second amplifier coupled to the output of said phase inverter, and a third amplifier fed by the other pulse of said pair, there being a common load resistor for said last two amplifiers, and an output circuit coupled to said common load resistor.

16. A pulse generating system comprising a first normally non-conducting electrode structure having a grid, anode and a cathode, a second normally conducting electrode structure having a grid, anode and a cathode, a differentiator circuit coupled between the anode of said first structure and the grid of said second structure, third and fourth electrode structures each including grid, cathode and anode electrodes, a common cathode resistor for the cathodes of said second, third and fourth electrode structures, whereby the voltage developed across said common cathode resistor due to current flowing in said second structure biases said third and fourth structures below cut-off, a transformer having a primary winding coupled across the anodes of the third and fourth structures, and a secondary winding for deriving output pulses from said transformer, and a circuit for applying a recurring waveform to the grid of said first structure of such polarity and magnitude as to cause said first structure to conduct, to thereby bias said second structure to the anode-current cut-off condition and cause said third and fourth structures to conduct.

17. A pulse generating system comprising a first normally non-conducting electrode structure having a grid, anode and a cathode, a second normally conducting electrode structure having a grid, anode and a cathode, a differentiator circuit coupled between the anode of said first structure and the grid of said second structure, third and fourth electrode structures each including grid, cathode and anode electrodes, a common cathode resistor for the cathodes of said second, third and fourth electrode structures, whereby the voltage developed across said common cathode resistor due to current flowing in said second structure biases said third and fourth structures below cut-off, a transformer having a primary winding coupled across the anodes of the third and fourth structures, and a secondary winding for deriving output pulses from said transformer, and a circuit for applying a recurring waveform to the grid of said first structure of such polarity and magnitude as to cause said first structure to conduct, to thereby bias said second structure to the anode-current cut-off

condition and cause said third and fourth structures to conduct, said common cathode resistor having such value that said third and fourth electrode structures operate as class A amplifiers when said second structure is biased below cut-off.

18. A pulse generating system comprising a first normally non-conducting electrode structure having a grid, anode and a cathode, a second normally conducting electrode structure having a grid, anode and a cathode, a differentiator circuit coupled between the anode of said first structure and the grid of said second structure, third and fourth electrode structures each including grid, cathode and anode electrodes, a common cathode resistor for the cathodes of said second, third and fourth electrode structures, whereby the voltage developed across said common cathode resistor due to current flowing in said second structure biases said third and fourth structures below cut-off, a transformer having a primary winding coupled across the anodes of the third and fourth structures, and a secondary winding for deriving output pulses from said transformer, and a circuit for applying a recurring waveform to the grid of said first structure of such polarity and magnitude as to cause said first structure to conduct, to thereby bias said second structure to the anode-current cut-off condition and cause said third and fourth structures to conduct, said common cathode resistor having such value that said third and fourth electrode structures operate as class A amplifiers when said second structure is biased below cut-off, and means for applying a modulating voltage to at least one of said third and fourth electrode structures.

19. A pulse generating system in accordance with claim 18, characterized in this, that said last means includes a phase inverter tube.

20. In a pulse generating and modulating system, the method which includes producing two simultaneously occurring pulses of the same relative polarity and equal amplitude in the absence of modulation, modulating the amplitudes of said pulses relative to each other in accordance with a signal, and converting said two pulses to a single pulse whose amplitude is modulated plus or minus relative to a reference value.

21. A pulse generating system comprising a pair of vacuum tube electrode structures, each including a control electrode and an anode, a circuit for periodically causing said structures to become simultaneously conductive and then non-conductive, means biasing said structures to operate as class A amplifiers when they become conducting, a circuit for supplying a modulating voltage to the control electrode of at least one of said structures, and leads coupled to said anodes for deriving from said structures a pair of simultaneously occurring pulses of the same relative polarity when said structures simultaneously change from one current condition to the other.
